CANDELABRA

Andrew Reiz, Kansas City, Mo.

Application June 21, 1955, Serial No. 36,621

Term of patent 14 years

(Cl. D48—2)

Fig. 1

Fig. 2

The dominant features of my new design are shown in solid lines.

I claim:

The ornamental design for a candelabra, as shown and described.
